his Attorney

UNITED STATES PATENT OFFICE.

RALEH E. HELMER, OF CLEVELAND, OHIO, ASSIGNOR TO THE RE FIL BROOM COMPANY,
A CORPORATION OF OHIO.

BROOM.

Application filed October 8, 1923. Serial No. 667,169.

This invention relates to brooms and the like, and has for its principal object to provide a broom having a removable straw portion which is easy to attach to the handle, 5 securely and rigidly held in position, and is neat in appearance.

Another object of the invention is to provide the straw portion for said broom of such construction that it is less expensive to 10 manufacture than in the ordinary construction of brooms having the straw portion bound by wire to the handle.

With the above and other objects in view, the invention will be hereinafter fully described as illustrated in the accompanying drawings, and the novel features thereof will be distinctly pointed out in the appended 15 claims.

In the drawings similar characters of reference are used to indicate corresponding parts.

Figure 1 is a side elevation of a broom constructed in accordance with my invention, the hollow body being in section to 25 better show the construction.

Fig. 2 is an edge view of Fig. 1, the holding member being similarly shown, the hollow body being shown in section,

Fig. 3 is a plan view illustrating one-half 30 of the straw portion of the broom bound together by a strip of cloth, and

Fig. 4 is a perspective view illustrating the head of one-half of the straw portion of the broom after completion for sewing to 35 the other half.

Referring to the drawings, 1 represents a hollow body having inwardly tapering sides 2 and 3 forming a lower elongated open end 4, and terminating in an upper center cylindrical neck 5, which is internally threaded 40 at 6 for receiving the threaded portion 7 of the handle 8. The inner surfaces of the tapering sides 2 and 3 of said hollow body near their lower ends are provided with longitudinal concave depressions 9 and 10, which form opposite ridges or beads at 45 11-12 and 13-14. The straw portion, indicated by 15, comprises similar halves 16 and 17, which are fixed together by one or 50 more rows of stitching as at 18. Each half of the straw portion of the broom above said rows of stitching is compressed into a head as indicated by 19 and 20, the inner sides of which are inclined at 21 and 22 respectively

to form a tapering or wedge shaped recess 55 23, and the outer sides thereof are formed with longitudinal grooves 24-25 and 26-27 corresponding to the ridges or beads 11-12 and 13-14 of the sides 2 and 3 respectively for receiving the same. Between the longitudinal grooves 24-25 and 26-27 are formed convex surfaces 28 and 29 corresponding to the concave depressions 9 and 10 of the sides 2 and 3 for registering therewith. In order to prevent the tearing apart of the 60 head of the straw portion, a strip of cloth, canvas or other suitable material 30 is cemented or otherwise fixed to the inner inclined sides thereof. For the purpose of forcing the heads 19 and 20 upwardly against 65 the inner surfaces of the inclined sides 2 and 3 of the hollow body so that the longitudinal grooves 24-25 and 26-27 will engage the ridges or beads 11-12 and 13-14, and the convex surfaces 28 and 29 will engage the 70 concave depressions 9 and 10, a wedge 31 constructed of spring sheet material is arranged in the wedge shaped recess 23. The upper edges of the sides of the spring wedge 75 31 are bent outwardly at 32 to serve as flanges for strengthening said sides and for engaging the upper ends of the heads 19 and 20 of the straw portion to prevent forcing of said spring wedge tightly into the recess 23 and thereby make it difficult to remove 80 the same. The lower end of the handle 8 is conical, as indicated by 33, and is adapted to enter the space between the sides of the spring wedge 31 and force the sides thereof 85 outwardly as the handle is rotated and thereby advanced due to the action of the threaded portion 7 thereof in the threaded neck 5 of the hollow body 1.

An important feature of this invention is the making of the removable straw portion 95 of the broom. Each half of said straw portion is formed separately and then sewed together at 18. The head portion of each half is first dipped into suitable vulcanizing material such as rubber, a strip of cloth, canvas, or other suitable material is wound around 100 said head portion to form a band 34 for holding same together, which head portion is then compressed into the form shown and described, held under compression, and subjected to vulcanizing heat, all by any suitable means as for instance a heated press. Said band of cloth is cut at 35 and 36 and

the portion thereof at the outer side of the head portion is removed, thereby leaving the strip 30 at the inner side thereof.

From the drawings and description, it is readily seen that the straw portion of the broom is comparatively inexpensive to manufacture, that the same is easily fixed into the hollow body 1 and securely and rigidly held in position by the conical end 33 of the handle 8 spreading the sides of the spring wedge 31 as the handle is turned and this forces the heads 19 and 20 thereof outwardly and their convex surfaces 11 and 12 into engagement with the concave depressions 9 and 10 of the sides 2 and 3 of the hollow body. It will be understood that slight changes in the details of construction may be made within the scope of the claims.

Having fully described my invention, what I claim is:

1. In a broom, the combination of a straw portion, a hollow body for the straw portion, a wedge constructed of spring sheet material, the wedge having the longitudinal edges of its sides bent outwardly to form flanges for strengthening said sides and for engaging the straw portion to limit the movement of the wedge, and means for spreading the spring wedge to cause it to secure the straw portion in said hollow body, substantially as described.
2. In a broom, the combination of a straw portion, a hollow body, the straw portion having spaced heads for insertion in the hollow body, a wedge formed by bending spring sheet material, the wedge having its longitudinal side edges bent outwardly to form flanges for strengthening same and for engaging the ends of said heads, and means for spreading the spring wedge to cause it to secure the straw portion in said hollow body, substantially as described.
3. In a broom, the combination of a straw

portion, a hollow body, the straw portion having spaced heads for insertion in the hollow body, a strip of cloth fixed to the heads for holding same, a wedge formed of channeled spring sheet material, and means for spreading the sides of the spring wedge to cause them to engage said heads for securing same in said hollow body, substantially as described.

4. In a broom, the combination of a straw portion, a hollow body, the hollow body having inwardly tapering sides, longitudinal beads at the inner surfaces of said tapering sides, said straw portion having spaced heads for insertion in the hollow body, the heads having depressions for registering with said beads, a wedge formed of channeled spring sheet material for insertion in the space between said heads, the wedge having its longitudinal side edges bent outwardly to form flanges for strengthening same and for engaging the ends of said heads, a handle threaded in said hollow body, and the handle having a conical end for engaging the sides of said spring wedge for forcing said sides against said heads to cause same to engage the tapering sides of said hollow body, substantially as described.

5. In a broom, the combination of a straw portion, a hollow body, the straw portion being formed of halves, each half of the straw portion having a head, the heads being arranged opposite each other and in spaced relation, a strip of cloth at the inner side of each of said heads, said heads being disposed in said hollow body, a spring wedge arranged between said heads, and means for spreading the spring wedge to cause it to secure said heads in said hollow body, substantially as described.

In testimony whereof I affix my signature.

RALPH E. HELMER.
